Primary Examiner — Cynthia M. Chin

(57) **CLAIM**

The ornamental design for a multi-functional educational toy flower bead, as show and described.

DESCRIPTION

FIG. 1 shows a perspective side view where the bead is slightly tilted to the right side, showing my new design; FIG. 2 shows a side view of the bottom half of the bead, shown separately for the ease and clarity of illustration; FIG. 3 shows a perspective view of the bottom half of the bead, shown separately for the ease and clarity of illustration; and, FIG. 4 shows another perspective view of the top half of the bead, shown separately for the ease and clarity of illustration.
